UNITED STATES PATENT OFFICE.

CHARLES PABST, OF PHILADELPHIA, PENNSYLVANIA.

LAMP.

SPECIFICATION forming part of Letters Patent No. 321,522, dated July 7, 1885.

Application filed April 15, 1884. (No model.)

To all whom it may concern:

Be it known that I, CHARLES PABST, of the city and county of Philadelphia, Pennsylvania, have invented a new and Improved Lamp, 5 of which the following is a full, clear, and exact description.

The object of my invention is to provide a new and improved kerosene-lamp which is simple in construction, ornamental, and can 10 be easily adjusted on its support.

Reference is to be had to the accompanying drawings, forming part of this specification, in which similar letters of reference indicate corresponding parts in all the figures.

15 Figure 1 is a side view of my improved lamp. Fig. 2 is an enlarged longitudinal partly-sectional view of the upper part of the standard and the socket of the bell-carrier, and Fig. 3 is a side view of a modification of the 20 same.

A standard, A, either solid or hollow, is secured on a base, B.

25 A ring, C, for receiving the lamp-body D, is held on the lower end of a rod or carrier, E, provided with an eye or ring, F, through which the standard passes, and with an apertured arm, G, through which the standard A also passes.

An ornamental balancing-weight, H, is held 30 on the free end of the arm G. A pin, J, is secured to a wire, K, having its opposite end secured to a ring, I, held loosely on the standard, which pin J is passed through one of a series of apertures, L, in the standard A, the 35 carrier resting on the said pin.

A rod, M, is provided at its lower end with a socket, N, for receiving the upper end of the rod E or the upper end of the standard A.

40 A reflector, O, is provided with an eye, P, through which the rod M passes, the said eye resting on a shoulder of the rod E; or the eye P may be slipped over the upper end of rod E, as shown in Fig. 1. The upper end of the rod M is bent, and a smoke-bell, Q, is suspended from the upper bent end of the rod, the said bell being held above the chimney R of the lamp D.

45 The weight H counterbalances the lamp and turns with the lamp, which can easily be turned 50 around the standard and the light thus thrown in any desired direction.

If the rod M is held on the rod E, the bell will turn with the lamp and will always be held above the chimney.

If the balance-weight H is removed, the carrier can be hung on a hook, S, on the wall or other object by means of the ring F.

The carrier can easily be raised or lowered.

Having thus described my invention, I claim as new and desire to secure by Letters Patent—

1. In a lamp, the combination, with the standard A, having apertures L, of a lamp-carrier adapted to turn on the said standard, the pin J, the chain K, and the ring I, substantially as herein shown and described. 65

2. In a lamp, the combination, with the standard A, of a revolving lamp-carrier, the vertical rod E thereon, and the rod M, having a socket, N, in its lower end, and bent at its upper end to allow of a smoke-bell being suspended therefrom, substantially as set forth. 70

3. The combination, with the standard A, of a revolving lamp-carrier, C, mounted thereon and provided with the removable balancing-weight H, substantially as set forth. 75

4. The combination, with the rod E, having a lamp-holding ring, C, a ring, F, and a reduced shouldered portion at its upper end, of a smoke-bell support having a socket to engage said shouldered portion, substantially as set forth. 80

5. In a lamp of the character described, the upright rod E, having the lamp-supporting ring on one side and the eye F and apertured arm G on its opposite side, the aperture of the arm G being in vertical alignment with the eye F, whereby the rod, with its parts, may be applied to a vertical lamp-standard or to a hook on the wall, substantially as set forth. 85

6. In a lamp, the combination, with a fountain-holding ring and the upright rod projecting from one side thereof, of a smoke-bell rod held to the said upright rod, and a reflector provided with an eye through which said smoke-bell rod passes, substantially as set forth. 90

CHARLES PABST.
